UNITED STATES PATENT OFFICE.

WILLIAM A. COLE, OF BELDING, MICHIGAN.

MACHINE FOR HANGING WALL PAPER.

Application filed January 12, 1928. Serial No. 246,232.

This invention relates to wall paper hanging machines, and has for one of its objects to provide a machine of this character which shall embody a novel, simple, inexpensive and highly efficient frame for supporting the paste receptacle, pasting roller, paper carrying spindle, smoothing roller and paper cutting means of the machine.

The invention has for a further object to 10 provide a machine of the character stated wherein the paste receptacle shall be adjustable to adapt the machine for applying paper to ceilings or side walls and which shall be provided with novel means for maintaining 15 the paste receptacle in adjusted position.

The invention has for a further object to 20 provide a machine of the character stated wherein the pasting roller shall be arranged to extend through and above the open upper 25 side of the paste receptacle and wherein the paste receptacle shall be provided with means for removing surplus paste from the roller.

The invention has for a still further object 25 to provide a machine of the character stated wherein the paper cutting means shall embody a fixed blade, a movable blade, means 30 yieldingly holding the movable blade in closed position, and means under the control of the operator for holding the movable blade in 35 opened position until such time as the paper is to be cut.

The invention is hereinafter more fully described and claimed, and illustrated in the 35 accompanying drawings, wherein:

Figure 1 is a sectional view taken on a vertical plane extending centrally and longitudinally through the machine,

Figure 2 is a sectional view taken on the 40 vertical plane indicated by the line 2-2 of Figure 1,

Figure 3 is a view in side elevation of the machine, the operator controlled means being shown in a position to hold the movable 45 blade in opened position, and

Figure 4 is a view in side elevation of a portion of the machine illustrating the operator controlled means in blade releasing position.

The machine comprises a U-shaped frame 1. The cross member 2 of this part is provided at a point centrally between its ends with a depending socket member 3 for the reception of the upper end of a handle or staff 4. Arms 5 extend rearwardly from the side

members 6 of the frame 1. The arms 5 are secured to the frame members 6 at points between the ends of the latter. Braces 7 are secured to the rear ends of the arms 5 and to the upper ends of the frame members 6. The 60 overlapping portions of the arms and frame members 6 are provided with bearings 8, the overlapping portions of the arms and braces 7 are provided with bearings 9, and the overlapping portion of the frame members and 65 braces are provided with bearings 10.

A semi-cylindrical paste receptacle 11 is rockably supported within the frame 1 by a shaft 12 which is journaled in the bearings 8. A pasting roller 13 is rotatably supported 70 within the paste receptacle 11 by the shaft 12, and it is provided with a fabric covering 14. A scraper 15 is pivoted, as at 16, to the rear edge of the paste receptacle 11, and a scraper 17 is pivoted, as at 18, to the front edge of the 75 paste receptacle. The scrapers 15 and 17 rest at their upper free edges upon the pasting roller 13 above and at opposite sides of the axis of the roller, and they function to limit the amount of paste applied by the roller to 80 the paper. The paste receptacle 11 is held against rocking movement by means of a bolt 19 which is slidably mounted in a casing 20 carried by the frame 1 and engages a socketed boss 21 carried by the paste receptacle. The casing 20 extends upwardly from the frame member 2, and the boss 21 extends downwardly from the bottom side of the paste receptacle 11. The bolt 19 is supported in the boss 21 by a spring 22 mounted within the 90 casing 20, and it is adapted to be retracted by a pin 23 carried thereby and passing through a slot 24 in the casing 20. The bolt 19 holds the paste receptacle 11 with its upper open side in a horizontal plane while the machine 95 is being used to apply the paper to ceilings. The bolt 19 is also adapted to be used for the purpose of holding the paste receptacle 11 with its upper open side in a horizontal plane while the machine is being used to apply the 100 paper to side walls, and permit this to be done. The paste receptacle is provided at its rear side with a boss 25 similar to the boss 21 and adapted to be engaged by the bolt when the machine is held in such an angular position as 105 to permit the application of the paper to side walls.

A spindle 26 for the roll of paper 27 is journaled in the bearings 9. A smoothing roller 28 is supported immediately above the past- 110

ing roller 13 by a shaft 29 which is journaled in the bearings 10. While the device is being used, the paper passes between the pasting roller 13 and the smoothing roller 28 and about the smoothing roller. The inner side of the paper is coated with paste by the roller 13, and it is applied in a smooth condition to the ceiling or side wall by the roller 28.

The means for cutting the paper after a length thereof has been applied to the ceiling or side wall, comprises a fixed blade 30 and a movable blade 31. The blade 30 is secured to and between the braces 7, as shown at 32, and the blade 31 is pivoted at one end to the blade 30, as shown at 33. The blade 31 is provided at its free end with a reduced extension 34 which passes through the slot 35 in a guide 36 secured to one of the arms 5 and braces 7. The blade 31 is yieldingly held in closed position with respect to the blade 30 by a coil spring 37 which is secured to lugs 38 and 39 extending rearwardly from the blades 30 and 31, respectively. The paper passes between the blades 30 and 31, and while the machine is being used to apply paper to a ceiling or side wall, the blade 31 is held in opened position against the tension of the spring 37 by an eccentric 41 which is pivoted as at 42 to an arm 43 extending rearwardly from one of the frame members 6. The eccentric 41 is provided with an annular groove 44 in which the free end 34 of the blade 31 rides. A forwardly and downwardly extending arm 45 is carried by the eccentric 41, and a pull cord 46 extends downwardly from the front end of the arm. When the eccentric 41 is in the position shown by solid lines in Figure 4, the blade 31 is held in opened position against the tension of the spring 37, and the eccentric is moved into this position when preparing the machine for the application of a strip of the paper to a ceiling or side wall. After the application of the strip of paper, the eccentric 41 is moved into the dotted line position shown in Figure 4, through the medium of the pull 46, with the result that the blade 31 is freed for rapid movement into closed position by the spring 37. The length of paper applied to the ceiling or side wall will thus be neatly severed from the roll.

From the foregoing description, taken in connection with the accompanying drawings, the advantages of the construction and of the method of operation will be readily apparent to those skilled in the art to which the invention appertains. While I have described the principle of operation of the invention, together with the device which I now consider to be the best embodiment thereof, I desire to have it understood that the device shown is merely illustrative, and that such changes may be made when desired as are within the scope of the invention as claimed.

What is claimed is:—

65 1. A machine for hanging wall paper, com-

prising a frame, a paste receptacle rockably supported within the frame, means to hold the receptacle against rocking movement, a pasting roller rotatably supported within the paste receptacle, a smoothing roller rotatively supported within the frame above the pasting roller, arms extending rearwardly from the sides of the frame, and a paper roll supporting spindle journaled in the rear ends of the arms.

70 2. A machine for hanging wall paper, comprising a frame, a paste receptacle rockably mounted within the frame, means to hold the receptacle against rocking movement, a pasting roller rotatably supported within the paste receptacle, a smoothing roller supported within the frame above the pasting roller, arms extending rearwardly from the sides of the frame, braces extending from the sides of the frame to the rear ends of the arms, and a paper roll supporting spindle mounted in the rear ends of the arms.

75 3. A machine for hanging wall paper, comprising a frame, a paste receptacle rockably supported within the frame and provided with relatively spaced and socketed bosses, a casing carried by the frame, a bolt slidably carried by the casing for engagement in one of said bosses, a spring mounted in the casing and holding the bolt in one of the bosses, a pasting roller mounted within the paste receptacle, a smoothing roller mounted in the frame above the pasting roller, arms extending rearwardly from the frame, and a paper roll supporting spindle mounted in the arms.

80 4. A machine for hanging wall paper including a frame, a paste receptacle rockably supported within the frame, means carried by the frame and paste receptacle to hold the latter against rocking movement with respect to the frame, a pasting roller mounted within the paste receptacle, a smoothing roller mounted within the frame above the pasting roller, a paper roll supporting spindle, and means supporting the spindle from the frame.

85 5. A machine for hanging wall paper, comprising a frame, a paste receptacle rockably supported within the frame and provided with relatively spaced members, means carried by the frame and engaging one of said members to hold the paste receptacle against rocking movement with respect to the frame, a pasting roller mounted in the paste receptacle, a smoothing roller mounted in the frame above the pasting roller, a paper roll supporting spindle, and means supporting the spindle from the frame.

90 6. A machine for hanging wall paper, comprising a frame, a paste receptacle mounted within the frame and having its upper side open, a pasting roller mounted within the paste receptacle, blades pivotally connected to the paste receptacle and resting at their free edges upon the pasting roller above and

at opposite sides of its axis, a smoothing roller mounted in the frame above the pasting roller, a paper roll supporting spindle, and means supporting the spindle from the frame.

- 5 7. A machine for hanging wall paper, including a frame for holding wall paper for application to a wall, means for applying paste thereto, and means for cutting the paper comprising a fixed blade mounted on the frame, a movable blade pivoted at one end to said fixed blade, a spring yieldingly holding the movable blade in closed position, and means carried by the frame and releasably holding the movable blade in opened 10 position against the tension of the spring.

- 10 8. A machine for hanging wall paper, including a frame for holding wall paper for

application to a wall, means for applying paste thereto, and means for cutting the paper comprising a fixed blade mounted on 20 the frame, a movable blade pivoted at one end to said fixed blade, a spring yieldingly holding the movable blade in closed position, an eccentric pivotally mounted on the frame and provided with an annular groove for the 25 reception of the free end of the movable blade and adapted to be moved into a position to hold the movable blade in open position against the tension of the spring and into a position to release the blade, and an 30 operating member connected to the eccentric.

In testimony whereof I affix my signature.

WILLIAM A. COLE.
